UNITED STATES PATENT OFFICE.

FREDERICK KAUTZ, OF READING, PENNSYLVANIA, ASSIGNOR OF ONE-HALF TO
JOSEPH FEICHT, OF READING, PENNSYLVANIA.

AIRPLANE WING.

Application filed March 9, 1927. Serial No. 173,845.

This invention relates to airplanes and more particularly to the wings thereof.

It has been found that planes of the speedier type are hardest to control while 5 they are rising or descending due to their short wing spread.

The small spread deducts from the buoyancy of the craft making it difficult to control and hence dangerous to any flyer other 10 than a thoroughly experienced one.

If the wings were enlarged, in this type of plane, speed and quick motion, which is absolutely essential to a pursuit plane, would have to be sacrificed.

15 It is therefore the main object of this invention to provide means whereby the wing spread of the small crafts, namely mono-plane and bi-plane, may be increased or decreased as the occasion demands, that is, 20 while ascending or descending and the latter while travelling at a definite altitude.

A further aim is in the provision of an easy control, within the reach of the aviator, to accomplish the above purposes.

25 These and other objects, which will become apparent as the description progresses, are attained by the novel construction, combination and arrangement of parts, herein-after described and illustrated in the accompanying drawings, forming a material component of this disclosure, and in which:—

Figure 1 is a top plan view of a mono-plane equipped with an embodiment of this 35 invention, the wings being shown in an extended position.

Figure 2 is a similar view of the same showing the wings in a contracted position.

Figure 3 is a transverse sectional view 40 taken on line 3—3 of Figure 1, drawn to an enlarged scale.

Figure 4 is a front elevational view of the plane, the wings being in the same position as in Figure 2.

45 Figure 5 is a longitudinal sectional view showing the wing spread control in detail and drawn to an increased scale.

Figure 6 is a sectional view taken on line 6—6 of, and at a right angle to Figure 5.

50 Figure 7 is a top plan view of a bi-plane provided with an embodiment of the invention, shown in dash lines as contracted and in dot-dash lines as extended.

Figure 8 is a front elevational view of 55 the same.

In the drawings, the numeral 10 generally designates a conventional air-plane body of the mono or bi-plane type, having the usual rear wings 11, propeller 12 and landing wheels 13.

60 In Figures 1 to 6 inclusive, the body 10 is provided with outwardly directed, diagonal struts 14 on which is supported, above the body, an outer wing 15 having a longitudinal recess 16 extending therethrough and following the outer contour of the wing.

65 The wing is provided with anti-friction bearing 17 and 18 on its upper and lower walls respectively intermediate which is 70 slidable a pair of extensible wing sections 19 projecting from the ends of the wing.

The upper bearings 17 are provided with 75 adjusting screws 20 passing through to the top of the wing and by which the pressure on the sections 19 is regulated.

75 Vertically journaled in the center of the wing 15 is a pair of shafts 21 and 22 carrying pinions 23 and 24 respectively, the pinion 23 being engageable with racks 25 and 26 respectively in advance and in the 80 rear of the pinion and extending inwardly from the sections 19 and the pinion 24 engaging racks 27 and 28 similarly positioned.

85 Fixed on the end of the shaft 21, in a position easily accessible to the pilot is a crank handle 29 by which the racks are actuated, the racks being guided in cross bars 30 fixed in the recess 16 between the upper and lower walls of the wing 15, and receivable in recesses 31 formed in the inner ends of the sections 19 so as to permit complete retraction.

90 Thus, by revolving the handle 29 the pinion 23 and 24 will cause the racks 25, 26, 27 and 28 to move inwardly or outwardly, thereby increasing or decreasing the spread 95 of the wings 19 as the occasion may arise.

In Figures 7 and 8, a bi-plane is illustrated having its upper wing 30 supported on struts 31, the lower ends of which are secured to an outer wing casing 15' similar 100 to the wing 15 and in which is operable, wing sections 19', the mechanism being the same as above described and the wings 15' 19' forming the lower plane of the craft.

105 Thus it may be seen that a device has been disclosed, adapted for use with crafts of the mono and bi-plane type, whereby ascending and descending is improved and the dangers connected therewith reduced by giving the plane more buoyancy and balance. 110

It will also be noted that the means for accomplishing these purposes are very simple, easy to operate and can be manufactured at a low cost.

5 Although the foregoing is descriptive of the preferred embodiment of my invention, it is to be understood that changes may be made in sizes, proportions, shapes, etc., without the exercise of invention and within 10 the meaning of the claim appended hereto.

Having thus described my invention, what I claim as new and desire to secure by Letters Patent, is:—

In an airplane, a hollow outer wing, an

inner solid wing of reduced like section 15
slidable therein, grooved metal plates mounted
on the inner surfaces of the outer wing,
ball bearings positioned in the grooves in
the plates and contacting the inner wing,
set screws threaded in the outer wing, and 20
bearing against the plates to adjust the ball
bearings against the inner wings, and rack
and pinion means to move the inner wing
longitudinally in the outer wing.

In witness whereof I have affixed my signature. 25

FREDERICK KAUTZ.
